ALBERT COWELL, OF KIDDERMINSTER, ENGLAND.

DESIGN FOR A CARPET-PATTERN.

Specification forming part of Design No. 5,707, dated March 26, 1872.

To all whom it may concern:

Be it known that I, ALBERT COWELL, of Kidderminster, in the county of Worcester, in England, have invented a new and original Design for Carpets; and I do hereby declare that the following is a full, clear, and exact description thereof, which will enable others skilled in the art to make and use the same, reference being had to the accompanying photographic illustration forming part of the specification.

This invention relates to a new design of the figures that serve to make up the ornamentation of a carpet. It consists, first, in the interior and outward decoration of a rectangular figure, which contains a wreath of flowers arranged in lozenge form, and is embraced by a rich ornamental scroll, as shown. The invention also consists in the new decoration of a star-shaped figure, containing a square field with narrow rectangular sides, as is also clearly shown in the photograph.

I claim as my invention—

The design for a carpet containing the ornamentation herein specified and shown.
